HYPERFREQUENCY ELECTRON TUBE

Emile Touraton and René Zwobada, Paris, France, assignors to International Standard Electric Corporation, New York, N. Y., a corporation of Delaware

Application October 1, 1948, Serial No. 52,238
In France October 31, 1947

2 Claims. (Cl. 315—39)

The present invention relates to vacuum tubes operating at very high frequencies and more particularly to vacuum tubes of this type in which an electron beam flows through one or several circuits through which a progressive wave flows. Such tubes are used in particular as wide band amplifiers.

One object of the present invention relates to the manufacture of a vacuum tube in which the density of the electron beam is high, so as to increase the high frequency output of the tube.

Another object of the present invention is to eliminate the ions produced by the electron beam inside the vacuum tube and to rid the tube of one cause of parasitic oscillations which occur frequently in tubes of this kind.

According to one feature of the invention a hollow tubular electron beam is made to flow in the vicinity of a helicoidally wound ribbon. The useful high frequency field is the discontinuous field prevailing between the successive turns of the helix. The relatively large diameter of this helix makes it possible to operate the tube with a hollow tubular electron beam with a large cross section, a high intensity and low density, which are favourable conditions for the bunching of the electrons.

According to another feature of the invention the length of every turn is equal to one half of the mean wave-length or an odd number of half wavelengths of the wave to be amplified.

According to another feature of the invention a metal rod with the same axis as the helix is provided inside the helix.

This rod can provide a certain amount of attenuation so as to prevent the propagation of high frequency currents.

According to another feature of the invention this metal rod is brought to a potential different from the potential of the helix, thus establishing a radial electrical field between the rod and the helix.

According to another feature of the invention the electron beam is subjected at the same time to a uniform longitudinal magnetic field and to a radial electrical field. It is thus possible to vary the mean radius of the beam and its thickness by varying the intensities of the magnetic and the electrical fields.

According to another feature the radial elec-

2
trical field set up between the metal rod and the helix is useful for getting rid of the ions, which are collected either by the rod or the helix according to whether the radial electrical field is directed towards the rod or the helix.

The above and other features and objects of this invention and the manner of attaining them will become more apparent and the invention itself will be best understood by reference to the following description of an embodiment of the invention taken in conjunction with the accompanying drawings wherein:

Fig. 1 shows schematically a cross section of a vacuum tube incorporating features of the invention, and

Fig. 2 shows a cross section of a specific embodiment of the invention.

Fig. 1 shows an annular cathode provided with an electron emissive coating heated by a filament (not shown). The potential of the cathode will be considered as potential zero for the rest of the description. The electrons emitted by the cathode are directed in the form of a hollow tubular beam 2 by means of an electrode 3 at a null or slightly negative potential.

A longitudinal magnetic field is produced by a coil 4 coaxial with the tube; the magnetic field may be adjusted by varying the current applied to the coil by means of an exterior source of supply (not shown). The electron gun is subjected as a whole to the magnetic field set up by the coil. Due to the action of this magnetic field the electrons of the beam rotate about axis 5 of the tube.

35 Following the electron gun, is provided an electrode 6, which is shown schematically on the drawing as a cylindrical tube coaxial with axis 5 of the tube. This electrode is brought to a high potential. As a matter of fact this electrode 40 constitutes the circuit or circuits through which the progressive waves flow and may take the form of any appropriate structure used with such tubes.

Another electrode 7 located inside and coaxially with the tubular electrode 6 and with the same axis is brought to a high potential different from that applied to electrode 6. This electrode extends beyond electrode 6 as far as the inside of a collector electrode 8 which collects the electron beam. This collector electrode may be brought

to a higher potential than that applied to electrode 6 and may be located outside the magnetic field set up by the coil 4. The path of the electron beam through the various electrodes is shown on Fig. 1 starting in 9 near cathode 1 and terminating in 10 on the collector electrode 8.

The adjustment of the intensity of the longitudinal magnetic field and that of the radial electrical field make it possible to vary, within certain limits, the mean diameter and the thickness of the tubular electron beam 11 at the level of the oscillating circuit. The longitudinal field of the electrons which is low when the electrons leave the electron gun in 9 increases in the interval separating the electron gun from electrodes 6 and 7.

Line 6 is matched at both ends by means which have not been shown, but which may be constituted for example by wave guides or coaxial structures well known in the art.

Fig. 2 shows a specific embodiment of the vacuum tube represented schematically on Fig. 1. The tubular cathode beam is generated by an electron gun 12 comprising for instance a cathode 13 of annular shape at the end 14 of which is deposited an electron emissive coating, a concentrating electrode comprising members 15, 16 and 17. Member 17 is screwed inside element 16 and holds the cathode 13 by means of a mica disc 18 on which the said cathode is mounted.

Member 16 is screwed into member 15 which is held in place by three insulating rods 19 at 120° one from the other. The assembly of the electron gun is maintained in the glass envelope 20 by a conventional resilient arrangement (not shown).

A cylindrical electrode 21 following the electron gun is held by an insulating rod 22 extending inside members 16 and 17. The three rods 19 hold in place at one of their ends another tubular electrode 23 on which repose three insulating rods 24 at 120° one from the other (only one of these rods is shown on the drawing) in order to avoid confusing the drawings.

The helically wound ribbon 25 is held on place inside the tube, by the three insulating rods 24. This helix is provided at both ends with radiating antennae 26 and 27 which, with the input and output wave guides 28 and 29, terminate it with the appropriate impedances. The end lead of antenna 26 is connected to electrode 23 and the end lead of antenna 27 to electrode 30 similar to electrode 23. Electrodes 23 and 30 are thus brought to the same potential as ribbon 25. The collector arrangement comprises a collector electrode 31 at the end of the glass envelope 20.

Rod 32 is a lead for rod 34 located inside the collector electrode 31. This rod 34 is supported on the central metal electrode 35 by means of an insulating member 36 and the other end of the central electrode 35 is held in place by means of an insulating member 37 which is fixed to electrode 21. A resilient arrangement can be provided which tends to push electrodes 34 and 32 one against the other. This resilient arrangement is not visible on the figures and may be constituted for instance by a spring inside member 16.

The electrical connection of electrodes 21 and 34 with the central electrode 35 is made by means of small size conductors 38 and 39 wound in the shape of a spring which may be provided with a coating in order to present an increased attenuation. This connection is shown by way of example, but it is possible to use other connecting

means which do not disturb the high frequency field in the neighborhood of the insulating rods 36 and 37.

A magnetic field parallel to the axis of the electron beam is set up by coil 40 and the electron gun 12 is located inside this magnetic field. It is of course possible to use any other appropriate arrangement generating a magnetic field.

The centre part of the vacuum tube has been omitted in the drawing in order to reduce its size; the connections between the output leads 41 and the electrodes have not been shown for the sake of clarity. While wave guides 28 and 29 are used for the input and output connections, it is clear that other means known in the art may be used instead. Rod 34 is maintained inside the collector electrode 31 by an insulating ring 44.

In the arrangement shown in Fig. 2 an electromagnetic wave travels along the helix. There is no appreciable axial electrical component, and, therefore, it is possible to introduce axial electrode 35 without disturbing the electrical field inside the tube. On the other hand a D. C. radial electrical field, between the central electrode and the helix, makes it possible to collect the electrons in this region of the tube and therefore to suppress one cause of parasitic oscillations. This radial electrical field repulses the ions towards one or the other electrode according to the direction of the electrical field; the elimination of these ions improve the operative stability of the tube.

The distance between two consecutive turns of the helix is chosen in such a way that the time, taken by the electrons to flow over this distance, be equal to one half period of the applied high frequency wave. Thus the same electrons are always subjected to the same high frequency field in the different intervals. The ratio of the longitudinal field to the tangential speed of the electrons is such that the electrons flow substantially perpendicularly through the intervals of the helix. The ribbon can be uniformly attenuated along the helix or at given points.

While we have disclosed particular apparatus for carrying out our invention, it should be understood that such apparatus is submitted as illustrative of the invention only and not as a limitation on the scope thereof.

We claim:

1. A travelling wave vacuum tube comprising in combination means for generating a hollow tubular electron beam for flow along a given path, an helically wound conductor surrounding and coaxial with said beam path, a cylindrical metal electrode inside of and coaxial with said beam path, means for applying a longitudinal magnetic field axially of said beam path substantially co-extensive with the length of said helically wound conductor and means electrically connected to said conductor and said electrode to apply thereto a difference of D. C. potential.

2. A travelling wave amplifier tube comprising an electron gun for generating an annular beam of electrons, a collector for said electrons spaced from said gun to define a beam path therebetween, a wave input connection proximate said gun and a wave output connection proximate said collector, wave velocity retardation means connected between said input connection and said output connection, a cylindrical metal electrode positioned coaxially and centrally of said beam path, means for creating a magnetic field lengthwise of said beam path substantially co-extensive

with the space between said wave input connection and said wave output connection, and means for applying potential to said electrode whereby said potential and said field cooperate to remove ions from said beam path, said retardation means comprising a helically wound conductor spaced concentrically of said cylindrical electrode and outside said path.

EMILE TOURATON.
